UNITED STATES PATENT OFFICE.

CHARLES WARREN, OF ROCKFORD, ILLINOIS.

AUTOPNEUMATIC PLAYING DEVICE FOR MUSICAL INSTRUMENTS.

1,014,545.

Specification of Letters Patent.

Patented Jan. 9, 1912.

Application filed August 20, 1909. Serial No. 513,756.

To all whom it may concern:

Be it known that I, CHARLES WARREN, a citizen of the United States, residing at Rockford, in the county of Winnebago and State of Illinois, have invented new and useful Improvements in Autopneumatic Playing Devices for Musical Instruments, of which the following is a specification, reference being had to the accompanying drawings, forming a part thereof.

The purpose of this invention is to provide an improved construction for certain elements and portions of a pneumatic action and connections for the same for automatic playing of musical instruments, particularly designed for the interior player action of an automatic operable piano.

It consists in the elements, and features of construction shewn and described as indicated in the claims.

In the drawings:—Figure 1 is a fore-and-aft vertical section through the upper portion, including the manual of an upright piano equipped with this invention at the line 1—1 on Fig. 2. Fig. 2 is a partly sectional front elevation of the same, section being made through the pneumatic action at the line 2—2 on Fig. 1, another section being made at the line 2^x—2^x on Fig. 1. Fig. 3 is a detail plan view of the primary pneumatics for controlling the shut-off and regulating motor pneumatics of the vent valves and air connections for the same. Fig. 4 is a detail section at the line 4—4 on Fig. 2. Fig. 5 is a vertical axial section of a primary pneumatic and its valves for controlling the re-roll, take-up and reversing mechanism section being made lengthwise of the valves at the axis of the pneumatic diaphragm. Fig. 6 is a rear elevation of an automatic governor for the roll-actuating motor. Fig. 7 is a section at the line 7—7 on Fig. 6 on a slightly reduced scale. Fig. 8 is a detail section at the line 8—8 on Fig. 6. Fig. 9 is a section at the line 9—9 on Fig. 6. Fig. 10 is a horizontal section of the case showing the foundation board in top plan view. Fig. 11 is a partially sectional front edge elevation of a block containing several primary pneumatics and their valves, section being made in vertical plane through one of the valves, as at 11—11 of Fig. 10.

The structure represented in the drawings shows a customary construction of an up-

right piano, of which the familiar parts are represented by letters as follows: A is the foundation board underneath the manual keys, B, extending to the upright ends of the case, C; E the hammer action. The automatic playing devices comprise a pneumatic action which as a whole is indicated by the letter, F. It is mounted above the rear part of the manual keys, having a base board, F¹, which extends to the ends of the case and supported thereon. The controlling mechanism, comprising the tracker board, G, roll carriage, H, and rolls H¹, H², thereon, and motor, J, for the rolls, is located above the pneumatic action, the several elements constituting said controlling mechanism being mounted upon the carrying bar, K, supported on the ends of the case, the means for producing suction or exhaust tension for operating the pneumatic action comprises the pumbers, L, L, connected respectively with exhaust air bellows, M, M, which are mounted in vertical position just inside the two ends of the case beyond the lateral range of the manual. The two chambers, M, M, are connected by an air trunk, M¹, so that both are affected by the action of either of the pumbers, L, L, said pumbers, however, communicate directly each with the exhaust air bellows, M, at the corresponding end of the instrument; such connection being made by short air trunks, L¹, leading into valve chambers, M¹⁰, M¹⁰, which are mounted upon the fixed walls of the bellows, M, M, respectively, as clearly seen in the drawings.

The pneumatic action comprises primary pneumatic chambers, 1, of which there are a plurality for convenience of arranging the pneumatics for the several keys in a plurality of banks or levels as is customary. Except as related to this point of convenience, the chambers, 1, 1, may be regarded as constituting a unitary chamber. These primary pneumatic chambers are mounted in a unitary structure comprising two vertical end chambers, 2, 2, which connect and relatively position the primary pneumatic chambers 1, 1, which open into said end chambers. Each of the primary pneumatic chambers is partitioned intermediate its ends at any point which may be selected for dividing between the higher and lower parts, commonly distinguished as treble and bass

respectively. From the exhaust air chambers bellows, M, M, air trunks M², M², lead to the end chambers, 2, 2, respectively, their communication therewith being controlled by valves, 4, 4, in the end chambers, respectively, mounted for sliding upon the vertical wall thereof over the ports of inlet of said trunks. The unitary structure constituting the pneumatic action is strengthened by a longitudinal top board, F², which forms the top wall of the end chambers, 2, 2, and upon this top board there are mounted motor pneumatics, 5, 5, and 5^a, 5^a, connected respectively to the valves, 4, 4, for actuating them. Each of the valves has an operating stem, 4^a, extending up through the top of the chamber, 2, between the operating fingers, 6, 6^a, which project from the upper walls,—which are the moving walls,—of the pneumatics, 5 and 5^a, respectively. The finger, 6, on the pneumatic, 5, extends over the end of the valve stem, 4^a, for operating upon it for thrusting the valve downward as the pneumatic is collapsed. The finger, 6^a, extends over an adjustable stop, 4^b, which is mounted on the stem, 4^a, and may be set higher or lower on said stem so as to be encountered sooner or later in the collapsing action of the pneumatic, 5^a, the adjustment being made according to the extent to which it is desired to have the valve, 4, closed by the collapse of said pneumatic, 5^a, as hereinafter explained. For controlling the motor pneumatics, 5, 5, a duct, 7, extends in the top board, F², from the left-hand end thereof, which extends beyond the chamber, 2, at that end, opening into each of said pneumatics, 5, as seen in Fig. 2, and connected at the end in the overhanging portion of the top board by a flexible tube, 8, with a primary pneumatic, 9, mounted in a primary pneumatic chamber, 10, supported on the foundation board, A. A vent for the pneumatic, 9, is provided by means of a duct, 11, leading to a port, 12, in a valve block, 13, supported on said foundation board said port being controlled by a valve, 14, fulcrumed on the foundation board and terminating for manual operation at a convenient point at the front of the manual. For controlling the motor pneumatics, 5^a, 5^a, ducts, 15, 15^a, are formed in the top board, F², leading from the left-hand overhanging end thereof to said pneumatics respectively, and connected respectively at said overhanging ends by flexible tubes, 16, 16^a, leading to the primary pneumatics, 17, 17^a, in the primary pneumatic chamber, 10, from which vent ducts, 18, 18^a, lead to the ports in a block, 13^a, controlled by valves, 19, 19^a, respectively, positioned and fulcrumed similarly to the valve, 14, and terminating similarly at points convenient for manual operation at the front of the instrument. The primary pneumatic cham-

ber, 10, is connected with the left-hand exhaust air chamber bellows, M, by an air trunk, 20. From the construction thus far described, it will be understood that when the operator operates the valve, 14, for opening the vent port, 12, venting the pneumatic, 9, both the motor pneumatics, 5, 5, will be collapsed and fully close the valve, 4, shutting off air communication from the entire primary pneumatic action, putting said action out of service and preventing automatic playing. It will also be understood that upon operating the left-hand valve, 19, venting the primary pneumatic which controls the left-hand motor pneumatic, 5^a, the valve, 4, at that end will be operated for closing partially, to an extent determined by the adjustment of the stop, 4^b, on the valve stem, 4^a, thereby restricting the movement of air from the primary action and with the effect of softening the bass action; and that when the right-hand valve, 19^a, is similarly operated, similar effect is produced by means of the right-hand motor pneumatic, 5^a, partially closing the right-hand valve, 4; and softening the treble action.

As usual in automatic playing devices employing an air motor for actuating the rolls to propel the controller sheet, the same source of suction is made available for the pneumatic action and for the motor. For this purpose, an air trunk, 21, leads to the motor, its ultimate connection being through an intermediate means, which will be now described, with the right-hand exhaust air chamber bellows, M. The intermediate connections comprise a governing device consisting of a spring-expanded bellows, 22, which communicates by means of an air trunk, 23, with said right-hand bellows, M, and by means of an air-trunk, 24, with a valve chamber, 25, which in turn is connected with the air trunk, 21, thus completing the line of communication from the chamber, M, to the motor, J. Within the governing bellows, 22, there is a flexible valve, 26, which controls the port, 27, by which said bellows communicates with the air trunk, 24. This valve, 26, is preferably a spring fastened at one end to the fixed board, 28, of the bellows, 22, through which said port, 27, leads to the air trunk, 24, and extending longitudinally over said port, which is itself a long narrow slit adapted to be closed gradually by the spring valve, 26, when the latter is depressed at its free end and thereby straightened out along the surface of the board, 28, over the said slit or port, 27.

An adjusting screw, 29, is set through the moving member of the bellows, 22, for encounter with the free end of the spring valve, 27, to depress it to its seat by the collapse of said bellows, the outer end of the screw being accessible for manipulation to

vary the extent of seating of the valve relatively to such collapse. Both the passage for connection with the chamber, M, and that for connection with the motor are conveniently formed in the fixed board, 28, of said bellows, 22, and both of said passages,—whose portions contained in the board are denoted by reference numerals, 23^a and 24^a, respectively, are open through to the back 5 side of the board,—that is, the side opposite the moving member of the bellows—in ports, 23^b and 24^b, respectively, and a hood forming a by-pass chamber, 30, is mounted on said side of the board, 28, into which both of 10 said ports, 23^b and 24^b, open, so that the passages, 23 and 24, are connected through the by-pass chamber independently of their connection through the bellows, 22. The said connection through the by-pass chamber is 15 controlled by a valve, 31, located in the by-pass chamber and closing the port, 24^b. This valve is operatively connected with a pneumatic, 32, mounted outside the by-pass chamber, and having a stem or plunger, 33, for operatively 20 connecting it with the valve, extending through the wall of the by-pass chamber loosely enough for movement therein and for affording a restricted air communication 25 between the by-pass chamber and the pneumatic. The pneumatic is provided with an unrestricted air communication by means of a passage, 33^a, formed in the inclosing wall of the pneumatic and having connected with it an air duct, 34, which leads to vent-controlling means hereinafter described. The 30 spring, 55, for yieldingly expanding the bellows, 22, is preferably located outside said bellows, reacting between the stops, 35^a and 35^b, on the fixed and moving walls, respectively, of said bellows.

Upon considering the governor devices above described, it may be understood that whatever be the exhaust air tension produced in the right hand chamber, M, by the 35 pumbers, the resulting tension operative upon the motor, J, will be determined by the tension of the spring, 55; because whenever its resistance is overcome so far as to close the valve, 26, no further exhaust action is 40 communicated to the motor. The well understood purpose of this governing expedient is to maintain a governed speed of the motor which may be subject to regulation at will for governing the rate of playing, such 45 government being effected by means of a valve, 36, in the valve chamber, 25, which is interposed as noticed in the passage leading from the governor to the motor, such valve, 36, being operated at will to close or open to 50 any desired degree the port of communication of the trunk, 25, with the valve chamber, and having connections, 37, extending to a finger-piece, 38, for sliding the valve to vary said opening and regulate the speed 55 of playing. When the roll-operating mech-

anism is reversed for rewinding or re-rolling the controller sheet after completing the playing or for returning to a previous point for repeating any portion of the music, it is desirable that the motor should operate at 70 the maximum speed which can be given it by the degree of exhaust tension maintained in the chamber, M, and that the pneumatic action should be cut off from the exhaust air chambers during such re-rolling so as to 75 prevent playing at that time. In order that these results may be effected without detail attention to them separately by the operator is the purpose of the governing devices and connections described; and for carrying out 80 this purpose, the motor-operating mechanism has the reversing lever, 37^a, (whose operation for reversing the direction of driving,—that is, for shifting the action from playing to rewinding,—is familiar and need 85 not be explained) mounted as a lever arm extending off at right angles from the moving wall, 39, of a motor pneumatic, 40, the mechanism being adjusted by the reversing lever for operating the take-up roll for playing when the pneumatic, 40, is collapsed, and for rewinding when said pneumatic is expanded. At any convenient position, and as illustrated, in the foundation board, A, whose primary pneumatic, 41^a, is connected 90 by an air tube, 46, with the source of the air trunk, M¹, there is mounted a primary pneumatic chamber, 41, whose primary pneumatic, 41^a, is connected with its valves, 42 and 43, for closing the communication with 95 the chamber when the pneumatic is expanded and opening such communication when the pneumatic is collapsed. From the port controlled by the valves, 100 the duct, 44, leads to two connections, 105 one with a duct, 45, leading to the motor pneumatic, 40, the other with a duct, 34, above mentioned leading to the pneumatic, 32, so that both of said motor pneumatics are controlled by the primary pneumatic, 110 41^a. The vent duct, 48, for controlling the primary pneumatic, 41^a, leads from the port controlled by the valve, 14. From this construction, it will be understood that when the operator operates the valve, 14, for opening the port which it controls, the vent thereby afforded through the duct, 11, to the primary pneumatic, 9, causes the operation 115 of both the motor pneumatics, 5, 5, effecting complete shut-off by means of the valves, 120 4, 4, of air communication to the pneumatic action, and by means of the vent afforded through the duct, 48, to the primary pneumatic, 41^a, causes inflation of the motor pneumatic, 40, operating the reverse lever 125 for shifting the driving train from the take-up to the re-wind roll, and the inflation simultaneously of the pneumatic, 32, causing the valve, 31, to be opened, thus establishing 130 direct communication by way of the by-pass

chamber, 30, from the exhaust air chamber, M, to the motor giving the motor action free from control of the governing device; that is, at maximum speed. That is to say, 5 from the opening of said valve, 14, there simultaneously results, first, the shutting off of the pneumatic action preventing playing; second, the shifting of the driving connection from the take-up to the rewind roll 10 causing rewinding; third, the releasing of the motor from all government, causing it to act at maximum speed during rewinding.

I claim:—

1. In an autopneumatic playing mechanism for musical instruments, in combination with the pneumatic action, take-up and re-roll mechanism and reversing means for the same, a shut-off valve for the pneumatic action, a motor pneumatic operatively connected with the reversing means; a motor pneumatic operatively connected with the shut-off valve; primary pneumatics for controlling said motor pneumatics respectively, and a manually operable vent valve 25 controlling both said primary pneumatics.

2. In an autopneumatic playing mechanism for musical instruments, a pneumatic action comprising a primary pneumatic chamber; an air trunk communicating with such chamber; a shut-off valve controlling such communication; two motor pneumatics, both non-interferingly connected with such shut-off valve for operating the same; means limiting the valve actuating action of one 30 of the motor pneumatics adapted to cause the valve to be only partially closed by said pneumatic; primary pneumatics for controlling said motor pneumatics respectively, and manually operable vent valves for the 40 primary pneumatics.

3. In an autopneumatic playing mechanism for musical instruments in combination with a longitudinally extended primary pneumatic chamber and primary pneumatics 45 therein, said chamber being partitioned intermediate its ends; air trunks communicating with the two end portions respectively; a shut-off and regulating valve for controlling each of said communications; a shut-off 50 pneumatic and a regulating pneumatic operatively connected with each of said valves; means limiting the action of the regulating pneumatics to cause them to only partially close the respective valves; separate primary pneumatics for controlling each of said regulating pneumatics; a single primary pneumatic for controlling both the shut-off pneumatics, and manually operable vent valves for controlling said three primary pneumatics respectively.

4. In an autopneumatic playing mechanism for musical instruments, exhaust mechanism; a pneumatic action comprising a primary pneumatic chamber; an air passage 55 constituting means of communication from

said exhaust mechanism to such chamber; a valve controlling such communication; a motor pneumatic operatively connected with such valve; adjustable means for positively limiting the valve-closing action of the motor pneumatic; a primary pneumatic for controlling such motor pneumatic, and a manually operable vent valve for controlling the primary pneumatic.

5. In an autopneumatic playing mechanism, in combination with a pneumatic action, a shut-off valve for the same; a motor pneumatic for operating such shut-off valve; a primary pneumatic for controlling such motor pneumatic; an exhaust air chamber; 70 a pneumatic motor; take-up and re-roll mechanism operated thereby; a reversing means for said mechanism; a motor pneumatic which operates said reversing means; a governing device between the exhaust air 75 chamber and the motor; a by-pass around said governing device; a valve which controls such by-pass; a motor pneumatic which operates such valve; a primary pneumatic which controls both the last-mentioned 80 motor pneumatic and the motor pneumatic which operates the reversing means, and a manually operable vent valve for controlling both said primary pneumatics.

6. In an autopneumatic playing mechanism, in combination with a pneumatic action having a partitioned primary pneumatic chamber; shut-off valves controlling the partitioned portions respectively; separate motor pneumatics for operating said 100 shut-off valves; a primary pneumatic controlling both said motor pneumatics; an exhaust air chamber; a pneumatic motor; take up and re-roll mechanisms operated thereby; a reversing means for said mechanism; a 105 motor pneumatic operatively connected with said reversing means; a governing device between the exhaust air chamber and the motor; a by-pass around said governing device; a valve which controls such by-pass; a motor pneumatic which operates said valve; a primary pneumatic which controls both the last-mentioned motor pneumatic 110 and the motor pneumatic which operates the reversing means, and a manually operated 115 vent valve for controlling both said primary pneumatics.

7. In an automatic playing mechanism, in combination with a pneumatic action, a shut-off valve for the same and means for actuating it; an exhaust air chamber; a pneumatic motor; take-up and re-roll mechanism operated thereby; a reversing means for said mechanism; a motor pneumatic which operates said reversing means; a governing device between the exhaust and the air motor chamber; a by-pass around said governing device; a valve which controls said by-pass; a motor pneumatic which operates such valve; a primary pneumatic 120 125 130

which controls both the last mentioned motor pneumatic and the motor pneumatic which operates the reversing means, and a manually operable vent valve for controlling
5 said primary pneumatic.

In testimony whereof, I have hereunto set my hand, in the presence of two witnesses,

at Chicago, Illinois, this 7th day of August, 1909.
